ELASTIC-FLUID TURBINE

Application filed April 18, 1929. Serial No. 356,274.

The present invention relates to elastic fluid turbines and its object is to provide a construction whereby heat may be abstracted from the elastic fluid and converted into useful work in the turbine. To the above end the present invention consists in the devices and combination of devices hereinafter described and more particularly defined in the claims.

10 In elastic fluid turbines as at present constructed, the elastic fluid, commonly steam, is delivered to the rotor from the source of supply through an expanding nozzle whereby the pressure of the fluid is transformed into 5 velocity of flow and at the same time the temperature is substantially reduced. For example, in the well known type of turbine illustrated in the drawing, the steam may be delivered to the nozzle at a pressure of 350 15 pounds per square inch at a temperature of 700° F. As it traverses the nozzle the pressure is transformed into velocity and the temperature drops, say, to 212° F.

This high velocity steam makes several 20 passes through the buckets of the rotor, being delivered initially from the nozzle and being returned each time by the reversing buckets adjacent the nozzle. During its passages through the rotor the steam gives up its 25 velocity to perform useful work in propelling the rotor.

Since the turbine is not 100% efficient, a portion of the steam passes the rotor with loss of velocity, but without doing useful work.

30 The energy represented by this loss of velocity which is not absorbed as work, is transformed into heat and this is evidenced by the temperature of the exhaust steam which, in the example, would be, say, 360° F., or 110° higher than the temperature of the steam as it 35 is delivered by the nozzle to the rotor.

This rise in temperature as the steam passes through the rotor without doing useful work, not only evaporates any moisture 40 but thereafter goes back into the dry steam in the form of superheat. It is this heat in the exhaust steam resulting from failure of the rotor to absorb all the energy from the steam passing through it, which the present 45 invention utilizes and returns to the rotor in

the form of energy available for useful work.

Briefly, the present invention consists of means for transferring heat from the exhaust steam or other fluid to the nozzle or to the rotor or to both, and in the preferred construction illustrated in the drawing such transfer is effected by means of extended surface upon the nozzle segment and rotor, which surface, being exposed to the exhaust steam or other fluid readily absorbs heat therefrom.

55 Referring to the drawings which illustrate what is now considered to be the preferred form of the present invention as applied to a well known type of turbine, Fig. 1 is a vertical, axial section of the turbine embodying the present invention; Fig. 2 is a detail view on an enlarged scale of a portion of the turbine, partly in elevation and partly in transverse section, showing a nozzle segment and adjacent casing and rotor parts; Fig. 3 is a 60 top plan view of the nozzle segment; and Fig. 4 is a vertical section of the nozzle segment on the line 4—4 of Fig. 2, looking in the direction of the arrow.

65 The turbine illustrated in the drawings is of the type illustrated in my prior Patent No. 1,291,374, January 14, 1919, and comprises the usual rotor or wheel 1, which turns within a casing 2 supporting the stationary elements 70 of the turbine. The rotor is mounted upon the shaft 3 by which power is transmitted to the exterior of the casing through any suitable connection on the tapered and keyed end. The shaft turns in the bearing bushings 4 mounted on the sleeves 5 integrally formed 75 with the walls of the casing.

80 The particular turbine illustrated is of the non-condensing type and is provided with the special construction of bearing and lubricating means of said patent whereby leakage 85 from the interior or exhaust chamber of the turbine through the bearing outwardly is prevented, but since these details form no part of the present invention, description is 90 unnecessary, reference being had if desired to my prior patent.

95 One wall of the casing is formed as shown, with an annular steam chest 15 on its outer surface to the interior of which chest steam 100

is supplied from any suitable source through connections not illustrated in the drawings.

Within the casing are secured the nozzle segments 17, each having the customary steam passage 19 in connection with the chest for conducting steam to the expanding nozzle 21. While only a single nozzle segment is illustrated in the drawings, it is to be understood that a plurality of such segments will ordinarily be provided in accordance with the usual practice, such segments being spaced at equal distances around the interior of the casing.

The nozzle segment is provided with a plurality of reversing buckets adapted to receive steam after it has passed through the rotor buckets and re-direct it back into the rotor, all as is well known in this art. In the construction illustrated in Fig. 2, there are five of these reversing buckets 23 in the nozzle, one of which is in the rear of the nozzle, another is at the side of the nozzle, and the other three are beyond the nozzle in the direction of rotation of the rotor.

The rotor is provided at its periphery with the usual series of buckets 25 of which several are shown in Fig. 2.

The exhaust steam is finally discharged from the rotor buckets as they pass from beneath the end reversing bucket, and escapes into the casing of the turbine from which it is carried away through the exhaust opening 27 at the bottom of the casing.

The nozzle segments, it will be observed, being located within the turbine casing, are surrounded by the exhaust steam, and in order to enable the segments to absorb heat from such steam I have provided them with extended surface in the form of ribs or flanges, three of which, 29, are arranged peripherally in parallel relation along the outer face of the segment, while the other two, indicated at 31, extend laterally in opposite directions from the side walls of the segment. Thus that portion of the nozzle segment normally containing steam at a lower temperature than of the exhaust has means designed and adapted to absorb heat from the exhaust steam and transfer it to the live steam within the segment, thus increasing the energy in the steam and the capacity of the turbine for doing useful work.

In order to prevent the exhaust steam from absorbing heat from that portion of the nozzle segment lying between the nozzle and the steam chest where a relatively higher temperature is maintained, I have provided an insulating sleeve 33, which may be of any well known insulating material, formed in two parts and clamped in position by the metal strap 35.

In order to still further abstract heat from the exhaust steam and convert it into useful work, I have provided extended surface upon the rotor whereby heat may be transmitted

from the exhaust steam to the rotor buckets. This extended surface is in the form of concentric ribs or flanges 37, of which I have shown three in the drawings, formed upon the sides of the bucket carrying portion of the rotor. These ribs or flanges will be carefully machined and finished with a smooth and polished surface so as to reduce friction losses to a minimum.

The operation of the turbine herein shown and described is in general the same as that of my prior patent. The steam is supplied to the steam chest from the boiler and passes into the nozzles of the several segments within the casing. Owing to the expanding character of the nozzles, the pressure of steam is transformed into velocity of flow with a reduction of temperature.

The steam issuing at high velocity from the nozzle enters one of the rotor buckets and gives up a portion of its velocity and heat to drive the rotor. The steam from this rotor bucket is discharged into one of the reversing buckets of the nozzle segments and is redirected back into the rotor where it gives up more energy to drive the rotor, finally being discharged into the open casing.

During the passage of the steam through the rotor and reversing buckets, there is an increase in temperature of the steam due to the failure of the rotor to absorb in the form of work all of the energy liberated by the reduction in velocity of the steam. The steam is finally discharged from the rotor, therefore, at a higher temperature than that which would normally be maintained within the nozzle and the reversing buckets of the segment. Through the action of the fins or ribs upon the segment, some of the excess of heat in the exhaust steam is transferred to the segment and thence to the live steam within to increase the heat thereof and consequently its potential energy.

In the same manner the excess of heat in the exhaust steam is transferred through the concentric fins or ribs of the rotor to the rotor buckets and thence to the steam passing through them, thus further increasing the energy available to drive the rotor.

Owing to the curvature at the base of the nozzle buckets and of the rotor buckets, and to the consequent centrifugal action of the steam in passing through these buckets, the steam and particularly any moisture contained therein is brought into close contact with the metal of the nozzle segment and the rotor, thereby facilitating the transfer of heat from these parts to the steam.

While the present invention has been shown and described as embodied in a particular construction or type of turbine, it is to be understood that it is not limited either to such types or to the specific means illustrated, but may be embodied in other forms of turbine and in other specific devices within the

scope of the appended claims. Where in the claims the term "steam" is used this is to be taken to mean any elastic fluid whether steam, air, or other gas.

5 Having thus described the invention, what is claimed is:

10 1. The combination with a casing and rotor of an elastic fluid turbine, a nozzle segment located within the casing and exposed to the exhaust steam, the segment having a nozzle and reversing buckets formed therein and being provided with extended surface adjacent the nozzle and buckets for transferring heat from the exhaust steam to the live steam within the nozzle and buckets, and means 15 for preventing the transfer of heat to the exhaust steam from that portion of the nozzle segment adjacent the casing.

20 2. In an elastic fluid turbine the combination with a casing, of a rotor within the casing and exposed to the exhaust steam, the rotor being provided with buckets and with extended surface to absorb heat from the exhaust steam and transfer it to the buckets, 25 and a nozzle for delivering steam to the buckets.

30 3. In an elastic fluid turbine the combination with a casing, of a rotor within the casing and exposed to the exhaust steam, the rotor being provided on its outer peripheral face with buckets and on its sides adjacent the buckets with flanges to absorb heat from the exhaust steam and transmit it to the buckets, and a nozzle for delivering steam to the rotor 35 buckets.

40 4. In an elastic fluid turbine the combination with a casing, of a rotor within the casing and exposed to the exhaust steam, the rotor being provided with buckets and with concentric co-axial flanges to absorb heat from the exhaust steam and transmit it to the buckets, and a nozzle for delivering steam to the rotor buckets.

45 5. A nozzle segment for elastic fluid turbines comprising an arc-shaped body portion provided with an expanding nozzle and with reversing buckets on the inner face thereof, and with a plurality of peripherally disposed heat absorbing flanges on the opposite face.

50 6. The combination in an elastic fluid turbine of a casing, a rotor mounted to turn therein, and a nozzle segment exposed to the exhaust steam and being provided with means for absorbing heat from such steam.

55 7. The combination in an elastic fluid turbine of a casing in which the steam is exhausted, a rotor mounted to turn in the casing, and a nozzle segment located within the casing and exposed to the exhaust steam, said 60 segment being provided with extended surface to absorb heat from the exhaust steam.

65 8. The combination in an elastic fluid turbine of a casing, a rotor mounted in the casing, a nozzle segment having an expanding nozzle and reversing buckets formed there-

in, the segment being located in the casing and exposed to the exhaust steam, and being provided with a plurality of flanges for absorbing heat from the exhaust steam and transferring it to the live steam within the nozzle and buckets.

70 9. In an elastic fluid turbine the combination with a casing into which the steam is exhausted, of a rotor mounted to turn within the casing and exposed to the exhaust steam, the rotor being provided on its outer peripheral face with buckets and on its sides adjacent the buckets with thin, deep, concentric flanges divergently disposed with relation to one another to absorb heat from the exhaust steam and transmit it to the buckets, and a nozzle for delivering steam to the nozzle buckets.

75 10. A nozzle segment for elastic fluid turbines comprising an arc-shaped body portion provided with an expanding nozzle and with reversing buckets on the inner face thereof, and with a plurality of thin, deep, heat-absorbing flanges extending lengthwise of the segment.

80 11. In testimony whereof I have signed my name to this specification.

OLIVER D. H. BENTLEY.
